UNITED STATES PATENT OFFICE

2,169,612

COMBINATION SCRAPER, CARRIER, AND SPREADING MACHINE

Wesley K. McMillan, San Francisco, Calif., assignor to Emsco Derrick and Equipment Company, Los Angeles, Calif., a corporation of California

Application June 25, 1934, Serial No. 732,223

24 Claims. (Cl. 37—126)

My invention relates to the art of gathering, carrying, and discharging earth or other material, and relates particularly to earth handling apparatus which are used for scraping, levelling, transporting, and discharging earth, such as are commonly employed for levelling of ground, for building roads, excavating, grading, filling in, etc.; and my invention relates more particularly to a heavy duty earth scraper by means of which large amounts of earth may be economically handled.

It is an object of my invention to provide a machine which will gather, transport, and dump unusually large amounts of material with the expenditure of but a minimum amount of power.

In earth scrapers of the type in common use a large expenditure of power is required due to the fact that as the earth accumulates in the earth gathering or receiving means, this mass of earth must be pushed rearwardly into the gathering or receiving means in order to accommodate additional earth.

It is an object of my invention to provide a machine in which it is unnecessary for the earth as it is gathered to push rearwardly into the earth gathering or earth receiving means the mass of earth which has previously been accumulated.

It is another object of my invention to provide a machine of the character mentioned including material carrying units or compartments which are moved into receiving position, and when filled are moved into carrying position, and another unfilled unit or compartment moved into receiving position.

It is another object of my invention to provide a machine of the character pointed out in which the material or earth is retained in the material carrying units or compartments until the operator is ready to discharge or dump the load, and in which the material is then dumped directly from the machine at the desired location.

It is a still further object of my invention to provide a machine in which the digging and gathering stresses are transferred directly to the frame of the machine rather than to the material carrying units or compartments. This object of my invention is accomplished by the provision of earth removing means or a blade which is independent of the material carrying units or compartments and which is preferably secured directly to the frame.

It is another object of my invention to provide an earth retaining means which cooperates with the material carrying units or compartments in

retaining the gathered material in the compartments when in material carrying position.

It is a still further object of my invention to provide a machine which has an opening through which material is received into the material carrying units or compartments and is also discharged or dumped therethrough.

It is also an object of my invention to accomplish certain specific objects such as to provide a scraper which extends crosswise of the frame and in conjunction therewith a fluid actuated jack mechanism whereby the scraper, together with one end of the frame, can be raised or lowered to regulate the depth of cut made by the scraper when scraping and loading and also to regulate the position of the scraper above ground when unloading so that the scraper may function as a spreader; to provide means on the frame for securing and retaining the gravel, sand, or other material scooped up by the scraper, said means comprising a multi-compartment rotary drum or carrier; to provide power actuated means for imparting a step by step rotary motion to the carrier to bring the carrying compartments successively into loading position; and further, to provide means for retaining the material in the respective compartments of the carrier during transportation from the place of loading to that of unloading.

In the course of the following description I will describe in detail one specific embodiment of my invention which includes the various features, objects, and advantages pointed out heretofore.

In addition to the preceding, other objects, advantages, and particular features of my invention will be pointed out in the course of the following description.

I believe my invention to be broadly new in its entirety and in certain novel subcombinations which comprise the whole. My invention may be embodied in different forms, and therefore I do not wish to be limited to the specific embodiment disclosed herein, but wish my invention to be construed in accordance with the spirit and scope of the appended claims.

The combination scraper, carrier and spreading machine is shown by way of illustration in the accompanying drawings, in which—

Fig. 1 is a side elevation of the machine. 50
Fig. 2 is a rear end elevation.

Fig. 3 is a view similar to Fig. 2 showing the rear lifting frame and the hydraulic jack mechanism removed.

Fig. 4 is a plan view of the machine. 55

Fig. 5 is an enlarged horizontal section showing a portion of the rear lifting frame and the channel and rollers whereby the rear lifting frame is guided with relation to the main frame.

Fig. 6 is a longitudinal section of one end of the drive shaft and the bearing supporting the same.

Fig. 7 is a cross section taken on line VII—VII of Fig. 6.

Referring to the drawings in detail, and particularly Figs. 1 and 2, A indicates a main frame consisting of a rear cross plate 2 and a pair of side plates 3—3, the forward ends of which are brought together as indicated at 3a to terminate in a goose neck 4. This neck is secured by means of a swivel connection 5 to an axle 6 supported by a pair of front wheels 7 and as such forms a support for the forward end of the frame; the rear end of the frame being supported by a frame B, supported by a pair of rear wheels 8 in a manner hereinafter to be described.

Disposed within the main frame A between the side plates 3—3 and just ahead of the rear cross plate 2 is a cylindrical shaped rotary drum or carrier C. This carrier consists of a pair of circular end plates 9—9 suitably secured at opposite ends of a hollow shaft 10, which, in this instance, is square in cross section as shown in Fig. 7. Extending through the hollow shaft 10 is a shaft which serves two functions, first that of supporting the drum or carrier C, and secondly that of imparting a step by step rotary motion to the same.

The supporting and driving shaft is best illustrated in Fig. 6, and consists of a turned round portion or stub shaft 11 journaled in a roller or similar bearing 12 secured in the side plate 3 of the main frame. The stub shaft is provided with two square extensions 13 and 14, the extension 13 projecting outwardly and forming a support for the hub 15 of a driving sprocket 16; the hub being secured against endwise removal from the extension 13 by a thru bolt 17. The extension 14 has a plurality of angle bars 18 welded, or otherwise secured thereto, and these bars extend through a square collar 19 fitting the interior of the shaft 10, this collar functioning as a spline or driving connection between the shaft 11 and the shaft 10. The angle bars extend completely through the hollow shaft 10 and their opposite ends are welded or otherwise secured to an extension on a shaft identical to the shaft 11; that is, there are two stub shafts 11 journaled one at each side of the main frame, one stub shaft carrying the driving sprocket 16 and the other a driving sprocket 16a; the two shafts being splined by collars 19 to the central shaft 10 of the drum or carrier and as such form a support for the drum and carrier and also a means whereby the step by step rotary movement is transmitted thereto. The angle bars function to connect the stub shafts and also to prevent individual canting or tilting of the stub shafts in their respective bearings.

The stub shafts 11 connected by the angle bars 18 are removable in an endwise direction through either of the bearings 12 and this can be accomplished by removing the sprockets 16 and then exerting an endwise pull on the opposite sprocket. This feature is important as it provides a simple method of releasing the drum or carrier when it is to be removed for inspection, repair, etc. The splined collars 19 are also removable. They are freely insertable in the opposite ends of the shaft 10 and, when so inserted, their inward

movement is limited by pins 19a. When they are inserted, they are secured by the inner ends of the bearings 12, which are also removable as shown, hence if the splined collars become excessively worn and too much play develops it is only necessary to remove the drive shaft and the bearings 12. This leaves the splined collars free for endwise removal and replacement. Similarly, if the bearings 12 of the stub shaft become worn they may be readily removed for repair or renewal.

The manner of supporting and rotating the carrier having been described it is desired to point out that the carrier is divided into four compartments or material carrying units by a series of curved laterally disposed plates, such as indicated at 21, these plates being, riveted or welded at their inner ends to the shaft 10 and being similarly secured at their ends to the circular plates 9. They are, furthermore, braced and secured by laterally disposed plates 22 which, to a certain extent, divide each compartment longitudinally into two compartments. The outer ends of the curved plates form scoops which dig into the material being handled during the loading operation and as the carrier may be rotated either in one direction or another, as will hereinafter be described, double lips or scoops are formed by adding the curved plates indicated at 23.

The rear transverse plate 2 is curved as shown to conform to the shape of the carrier and to permit free rotation thereof. The plate 2 extends from the upper edge of the frame, see Fig. 1, to a point almost directly below the shaft 10. In its forward edge is formed and suitably secured a scraper blade 24 which is reinforced and supported by stools 25 in the usual manner. The blade 24 constitutes a material removing means which removes the earth from the surface over which the machine is operating and from which the material is delivered to the compartments or material carrying units. The blade 24 also acts as an earth levelling means during the dumping or discharging operation, as will be described later. The principal feature of securing the blade directly to the frame is that the stresses or forces incurred during the scraping or digging operation are transferred directly to the massive frame rather than the drum construction. The cross plate 2 serves three functions, first that of a brace or tie between the side plates 3—3; secondly, that of a support for the scraper blade 24; and third, that of an enclosure for one or more of the compartments formed in the carrier, for instance, the compartments indicated at 21a and 21b.

There is a second curved plate which extends crosswise of the frame, that is, which is disposed between the side plates 3—3, and that plate is indicated by dotted lines at 26. This plate is resiliently supported by springs 28 and as such may yield in the event cobbles, roots, pieces of wood, or the like, become lodged between the lower edge of the plate and the scoop ends of the plates 21. The curved plate 26 serves as a closure for the compartment 21c. The plates 2 and 26 constitute a material retaining means of my invention. The only compartment which remains uncovered is that shown at 21d. This is, however, partially closed by the bottom portion of the cross plate 2 and the scraper 4, and considerable material can thus be carried when the other three compartments are loaded. The opening between the lower part of the plate 26

and the blade 24 constitutes a receiving and discharge opening through which gathered material is received into the compartments and discharged therefrom.

In the operation of the machine as a whole, it is necessary to raise and lower the scraper 24 to regulate and cut and depth of loading and to also regulate its height above ground when unloading so that the scraper may function as a spreader. To permit such adjustment the rear supporting frame B is employed. The rear end of the main frame A is so connected with relation to the rear frame B that vertical movement may be imparted and this is accomplished as follows.

By referring to Figs. 1, 2, 3, 4 and 6, it will be noted that a pair of channel-shaped tracks are secured to the rear transverse plate 2, one at each end thereof, these tracks being indicated at 30. Disposed between the channel tracks are the downwardly extending arms of the rear frame B, and carried by the upper ends of said arms and extending into the channel-shaped trackways are rollers 32, said rollers and channel track forming an adjustable connection between the main frame and the rear frame whereby the main frame may be vertically raised or lowered as occasion demands. There are a pair of downwardly extending arms on the rear frame at each end thereof and these terminate in a horizontal bar 33, said horizontal bar and the downwardly extending arms on the frame being connected by cross bars 34 and crossing bars 35 so as to tie the frame transversely and imparting the greatest amount of rigidity possible.

The rear frame is supported by the wheels 8 previously described, and when it is desired to raise the rear end of the main frame with relation to the rear frame, it is accomplished by a hydraulic jack mechanism comprising a pair of cylinders such as indicated at 40-40. The lower ends of the cylinders are pivotally connected to the rear frame. Each cylinder carries a piston and a projecting piston rod 41 and these rods are pivotally connected to the main frame as at 42. Oil, air, or any other fluid medium is delivered to the lower ends of the cylinders through a pipe, such as shown at 44, and when pressure is applied the pistons are extended, hence lifting the rear end of the main frame upwardly with relation to the rear frame or lowering it as occasion demands.

By this mechanism it is possible to adjust the position of the scraper, either above or below the surface being traveled over, and the scraper may thus assume a cutting or scraping position or a spreading or leveling position as desired.

It will be understood that a machine of this character preferably trails behind a tractor, or a like motor vehicle, so as to be pulled thereby. Any suitable type of drawbar, such as shown at 46, is employed to form a connection between the machine and the tractor. Tractors of varying makes are usually provided with a power take-off shaft and where this is the case the power take-off shaft may be connected to the shaft indicated at 48. This drives a reduction gear mounted within the housing 49 and the reduction gear, in turn, drives a cross shaft 50 having sprocket gears at opposite ends thereof and through chains 51 power is transmitted to the sprockets 16 and 16a and to the drive shaft previously described. Any clutch mechanism not here disclosed may be employed for transmitting power from the power take-off shaft to

the shaft 48, hence making it possible to transmit rotary motion to the carrier C whenever desired. For instance, if the machine is scraping and loading, the main frame and the scraper 24 will assume the position shown in Fig. 1, and when the compartment 21d has been substantially filled power is transmitted to rotate the carrier until the next compartment assumes loading position. In filling a compartment the drum may be held stationary until it is completely filled and then may be rotated in a counter-clockwise direction, referring to Fig. 1, that is, forwardly and upwardly, or the drum may be rotated in a clockwise direction, thus carrying the gathered material rearwardly and upwardly. The operation of the drum may be intermittent or may be continuous; that is to say, the drum may remain stationary until a compartment is completely filled or it may be moved slowly so that as the compartment is being filled it gradually moves in order that when filled another compartment is ready to be brought into earth receiving position. When the compartment is continuously moved, it is found preferable to rotate the drum in a clockwise direction so that as the compartment becomes filled the earth is moved rearwardly and upwardly into such a position that it is carried in the compartment or material carrying unit. I have made special provision on the walls of each compartment so that the material may be engaged and moved in either direction. When the drum rotates in a counter-clockwise direction the curved portion 21 engages and moves the earth, and when the drum is rotated in a clockwise direction the plate 23 engages the material and moves it rearwardly. It will be seen that the material, in any event, is moved by being engaged by the walls of any one of the compartments rather than by additional earth accumulating at or in front of the blade 24, and for this reason the power required to pull the machine and to dig and gather the material is greatly reduced. The rear curved plate 2 which extends rearwardly from the scraper blade 24 is curved upwardly around the axis of rotation of the drum and constitutes a bowl into which earth gathered by the blade may pass during the forward movement of the scraper. The drum, including the walls 21, may constitute a loading means and during the loading of the scraper the drum may be rotated a clockwise direction in Fig. 1 so that one wall 21 moves rearwardly in the bowl 2 ahead of the earth which is being gathered by the scraper blade 24 and passes rearwardly into the bowl. An adjacent wall which is moving downwardly and then rearwardly passes into the bowl to the rear of the earth and may be employed to push the earth rearwardly and upwardly into the upper rearward part of the bowl. When it is desired to dump the earth, the drum may be moved in a reverse direction, with the result that the wall which followed the earth into the bowl now moves forwardly ahead of the earth, and the wall which during loading moved into the bowl ahead of the earth now moves forwardly in back of the earth and pushes the earth forwardly so that it may be dumped over the blade 24. When this is accomplished the hydraulic jacks are caused to raise the main frame so that the scraper will be supported at an elevation insuring plenty of clearance. The load may then be hauled wherever it is to be dumped and, if it is desired to level or spread the material as it is being dumped, the scraper can 75

again be vertically adjusted. Each compartment of the carrier is brought into dumping position and as it dumps the scraper blade spreads and levels the material, it being understood that the carrier is preferably rotated in a reverse direction while dumping so as to insure complete removal of all material.

Oil or other fluid to actuate the hydraulic jack mechanism may be supplied from the tractor and the pipe 44 may thus be extended from the machine to the tractor to a pump or other source of supply and a multi-port valve, or the like, may obviously be inserted in the line to regulate the flow.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:

1. A machine of the character described comprising a main frame adapted to travel over a surface to be treated, a scraper carried by said frame, a multiple compartment carrier to receive material scraped up by the scraper, means for imparting a step by step movement to the carrier to bring empty compartments successively into loading position rearwardly of the scraper and to move the loaded compartment away from loading position, and means for retaining material loaded into the compartments until they are returned to loading position.

2. A machine of the character described comprising a main frame adapted to travel over a surface to be treated, a scraper carried by said frame, a drum-shaped carrier horizontally disposed in the frame above the scraper, a plurality of laterally disposed plates extending longitudinally of the carrier and dividing the carrier into a plurality of compartments, means for imparting a rotary movement to the carrier to bring empty compartments successively into loading position rearwardly of the scraper and to move the loaded compartments away from loading position, means for retaining material loaded into the compartments until they are returned to loading position, and means for elevating the main frame to raise the scraper out of contact with the surface to be treated and to permit gravity discharge of the material in the compartments of the carrier.

3. A machine of the character described comprising a main frame adapted to travel over a surface to be treated, a scraper carried by said frame, a drum-shaped carrier horizontally disposed in the frame above the scraper, a plurality of laterally disposed plates extending longitudinally of the carrier and dividing the carrier into a plurality of compartments, means for imparting a rotary movement to the carrier to bring empty compartments successively into loading position rearwardly of the scraper and to move the loaded compartments away from loading position, and arcuate plates disposed crosswise of the main frame in front and behind the carrier to form a closure for certain of the loaded compartments so as to retain material loaded into the compartments until ready for discharge.

4. A machine of the character described comprising a main frame adapted to travel over a surface to be treated, a scraper carried by said

frame, a drum-shaped carrier horizontally disposed in the frame above the scraper, a plurality of laterally disposed plates extending longitudinally of the carrier and dividing the carrier into a plurality of compartments, means for imparting a rotary movement to the carrier to bring empty compartments successively into loading position rearwardly of the scraper and to move the loaded compartments away from loading position, and arcuate plates disposed crosswise of the main frame in front and behind the carrier to form a closure for certain of the loaded compartments so as to retain material loaded into the compartments until ready for discharge, one of said arcuate plates being resiliently supported to permit it to move away from the carrier if roots or other obstructions become interposed between the carrier and said plate.

5. A machine of the character described comprising a main frame adapted to travel over a surface to be treated, a scraper carried by said frame, a drum-shaped carrier horizontally disposed in the frame above the scraper, a plurality of laterally disposed plates extending longitudinally of the carrier and dividing the carrier into a plurality of compartments, means for imparting a rotary movement to the carrier to bring empty compartments successively into loading position rearwardly of the scraper and to move the loaded compartments away from loading position, said plates being curved in one direction to form scoop-like outer edges to scoop up material delivered to the carrier by the scraper, and a reversely curved scoop-shaped rib on the opposite side of each plate to permit reverse rotation of the carrier.

6. A machine of the character described comprising a main frame, wheels supporting the front of said frame, a scraper extending crosswise of the main frame and secured thereto, a wheel supported rear frame, a pair of spaced vertically disposed channel tracks secured to the rear end of the main frame, rollers mounted on the rear frame and projecting into the channel tracks, said rollers forming a connection between the main frame and the rear frame which permits vertical movement of the rear end of the main frame with relation to the rear frame, and a fluid actuated jack mechanism positioned between the two frames to raise or lower the rear end of the main frame so as to vertically adjust the position of the scraper.

7. A machine of the character described comprising a main frame, wheels supporting the front of said frame, a scraper extending crosswise of the main frame and secured thereto, a wheel supported rear frame, a pair of spaced vertically disposed channel tracks secured to the rear end of the main frame, rollers mounted on the rear frame and projecting into the channel tracks, said rollers forming a connection between the main frame and the rear frame which permits vertical movement of the rear end of the main frame with relation to the rear frame, a fluid actuated jack mechanism positioned between the two frames to raise or lower the rear end of the main frame so as to vertically adjust the position of the scraper, a multi-compartment carrier supported by the main frame to receive material scraped up by the scraper, and means for imparting a rotary movement to said carrier to bring empty compartments successively into loading position rearwardly of the scraper and to move the loaded compartments away from loading position.

8. A machine of the character described comprising a main frame, wheels supporting the front of said frame, a scraper extending crosswise of the main frame and secured thereto, a wheel supported rear frame, a pair of spaced vertically disposed channel tracks secured to the rear end of the main frame, rollers mounted on the rear frame and projecting into the channel tracks, said rollers forming a connection between the main frame and the rear frame which permits vertical movement of the rear end of the main frame with relation to the rear frame, a fluid actuated jack mechanism positioned between the two frames to raise or lower the rear end of the main frame so as to vertically adjust the position of the scraper, a multi-compartment carrier supported by the main frame to receive material scraped up by the scraper, means for imparting a rotary movement to said carrier to bring empty compartments successively into loading position rearwardly of the scraper and to move the loaded compartments away from loading position, and a plurality of arcuate plates secured to the main frame and disposed on opposite sides of the carrier to retain material delivered to the compartments of the carrier until ready for discharge.

9. In a machine of the character described a main frame, a drum-shaped carrier mounted in the frame, said carrier having a tubular shaft extending therethrough and secured in the carrier, a bearing in each side of the main frame and a driving shaft extending through said bearings and the tubular shaft, said drive shaft comprising a pair of stub shafts journaled in the respective bearings, bars extending through the tubular shaft and secured to the inner ends of the stub shafts, a spline connection between each stub shaft and the tubular shaft, an outwardly extending extension on each stub shaft, and driving means carried thereby.

10. In a machine of the character described, the combination of: a frame construction adapted to travel along a surface; material removing means connected to said frame construction adapted to remove material from said surface; means providing a plurality of compartments supported by said frame construction, and means on said frame for intermittently rotating said compartment means, said means being operable to move said compartments into position at the rear of said material removing means, whereby said compartment means can be positioned to receive material removed by said material removing means, to carry said material and to dump the same from said machine at the desired location.

11. In a machine of the character described, the combination of: a frame construction adapted to travel along a surface; a blade secured to said frame construction for operation on said surface; and means providing a plurality of compartments supported by said frame construction, and means associated with said frame and compartment means for intermittently rotating said compartment means, said means being operable to move said compartments into position at the rear of said blade, whereby said compartment means can be positioned to receive material removed by said blade and which material moves rearwardly over said blade, to carry said material and to dump the same from said machine at the desired location.

12. In a machine of the character described, the combination of: a frame construction adapted to travel along a surface; material removing

means connected to said frame construction adapted to remove material from said surface; a plurality of material carrying units supported by said frame construction; and means supported by said frame for moving said units successively into a position at the rear of said material removing means to receive material gathered by and passing rearwardly from said material removing means, said means being operable to maintain units containing said material in a stationary carrying position.

13. In a machine of the character described, the combination of: a frame construction adapted to travel along a surface; material removing means connected to said frame construction adapted to remove material from said surface; a plurality of material carrying units having an opening to receive and discharge material supported by said frame construction; means carried by said frame operable to move said units successively into a position to receive material gathered by said material removing means and to subsequently move said units into a carrying position; and retaining means arranged exteriorly of said material carrying units supported by said frame and cooperating with said units when said units are in carrying position, to assist in retaining said material therein.

14. In a device of the class described, the combination of: a frame construction adapted to travel along a surface; a plurality of compartments supported by said frame construction, each having a receiving, a carrying, and a dumping position; and operating means for said compartments for moving them successively into receiving position in which material is gathered, carrying position in which the gathered material is carried, said compartments being held in receiving position and being filled by earth gathered due to a forward movement of the device, and dumping position in which the gathered material is dumped directly from said compartments onto the surface over which said device is traveling.

15. In a device of the class described, the combination of: a frame construction adapted to travel along a surface; a plurality of compartments supported by said frame construction, each having a receiving, a carrying, and a dumping position; means for successively moving said compartments into and from said positions; and spaced walls arranged exteriorly of said compartments forming an opening through which material is received into and dumped from said compartments.

16. In a device of the class described, the combination of: a frame construction; a plurality of compartments supported by said frame construction and operatively connected together so that each compartment successively has a receiving position, a carrying position in which material may be carried while another compartment is in receiving or dumping position, and a dumping position in which material is gathered into the compartment, a carrying position in which the gathered material is carried until dumped from said device at the desired location, and a dumping position; and step-by-step means for moving said compartment into receiving position and from receiving position into carrying position, and for successively moving each of said compartments from carrying position into dumping position.

17. In a device of the class described, the combination of: a frame construction adapted to

- travel along a surface; a plurality of connected compartments supported by said frame construction; each successively having a receiving position, a carrying position in which material may be carried while another compartment is in receiving or dumping position, and a dumping position; and means for holding said compartments in their different positions and for moving them from one position to another.
18. In a device of the class described, the combination of: a frame construction adapted to travel along a surface; a drum providing a plurality of material carrying compartments; means for moving said drum so as to bring compartments thereof into loading position and to move loaded compartments away from loading position into carrying position; and material retaining means exteriorly of and in front and in back of said drum cooperating with said drum for assisting in retaining material in loaded compartments when in certain positions.
19. In a device of the class described, the combination of: a frame construction adapted to travel along a surface; unit providing means providing a plurality of material carrying units; means for moving said units to bring them successively into loading position and to move loaded units away from loading position into carrying position; and walls disposed exteriorly of and in front and in back of said unit providing means, said walls providing opening means through which material is received into and discharged from said units.
20. In a device of the class described, the combination of: a frame construction adapted to travel along a surface; unit providing means providing a plurality of material carrying units; means for moving said units to bring them successively into loading position and to move loaded units away from loading position into carrying position; walls disposed exteriorly of and in front and in back of said unit providing means, and providing opening means through which material is received into and discharged from said units; and material removing means secured adjacent said opening means for operating on said surface.
21. A machine of the character described comprising: a main frame adapted to travel over a surface to be treated; a scraper carried by said frame; a drum-shaped carrier horizontally disposed in the frame above the scraper; a plurality of laterally disposed plates extending longitudinally of the carrier and dividing the carrier into a plurality of compartments; means for imparting a rotary movement to the carrier to bring empty compartments successively into loading position rearwardly of the scraper and to move the loaded compartments away from loading position, said plates being curved in one direction to form scoop-like outer edges to scoop up material delivered to the carrier by the scraper; and a material engaging means on the opposite side of each plate to permit reverse rotation of the carrier.
22. In an earth scraper, the combination of: a frame construction adapted to travel along a surface, and having a scraper blade; a bowl positioned to the rear of said scraper blade; pivotally supported loading and dumping means including a pair of generally radially extended walls spaced from each other and movable into the bowl, one of which walls moves into said bowl ahead of the earth, and the other of which follows the earth during loading, said loading and dumping means having a stationary carrying position; and operating means for holding said loading and dumping means in said carrying position and for moving said loading and dumping means in either direction.
23. In an earth scraper, the combination of: a frame construction adapted to travel along a surface, and having a scraper blade, a substantially semi-cylindrical bowl positioned to the rear of said scraper blade; a rotatable loading and dumping means including a pair of walls spaced from each other and receivable in said bowl, one of which walls moves into said bowl ahead of the earth, and the other of which follows the earth during loading, said loading and dumping means having a stationary carrying position; and operating means for holding said loading and dumping means in said carrying position and for rotating said loading and dumping means in either direction.
24. In a device of the class described, the combination of: a frame construction adapted to travel along a surface; a blade supported by said frame construction; a plurality of compartments supported by said frame construction, each having a receiving position adjacent said blade, a carrying position, and a dumping position; and means for holding said compartments in their different positions and for moving them from one position to another.

WESLEY K. McMILLAN.

CERTIFICATE OF CORRECTION.

Patent No. 2,169,612.

August 15, 1939.

WESLEY K. McMILLAN.

It is hereby certified that error appears in the printed specification of the above numbered patent requiring correction as follows: Page 5, second column, line 56, beginning with "16. In a device" strike out all to and including the word and period "another." in line 9, first column, page 6, comprising claims 16 and 17, and insert instead the following -

16. In a device of the class described, the combination of: a frame construction; a plurality of compartments carried by said frame construction and each having a receiving position in which material is gathered into the compartment, a carrying position in which the gathered material is carried until dumped from said device at the desired location, and a dumping position; and step-by-step means for moving said compartment into receiving position and from receiving position into carrying position, and for successively moving each of said compartments from carrying position into dumping position.

17. In a device of the class described, the combination of: a frame construction adapted to travel along a surface; a plurality of compartments supported by said frame construction and operatively connected together so that each compartment successively has a receiving position, a carrying position in which material may be carried while another compartment is in receiving or dumping position, and a dumping position; and means for holding said compartments in their different positions and for moving them from one position to another.;

and that the said Letters Patent should be read with this correction therein that the same may conform to the record of the case in the Patent Office.

Signed and sealed this 3rd day of October, A. D. 1939.

(Seal)

Henry Van Arsdale,
Acting Commissioner of Patents.
